UNITED STATES PATENT OFFICE.

HENRY W. FISHEL, OF NEW YORK, N. Y., ASSIGNOR TO HIMSELF AND THEODORE H. FISHEL, OF NEW YORK, N. Y., COPARTNERS TRADING AS FISHEL, NESSLER & COMPANY, OF NEW YORK, N. Y.

JEWEL-BAR.

No. 884,979.

Specification of Letters Patent.

Patented April 14, 1908.

Application filed July 12, 1907. Serial No. 383,440.

To all whom it may concern:

Be it known that I, HENRY W. FISHEL, a citizen of the United States, residing at the borough of Manhattan, city of New York, in the county of New York and State of New York, have invented a certain new and useful Improvement in Jewel-Bars, of which the following is a specification, reference being had therein to the accompanying drawings, forming part thereof.

In the manufacture of the cheaper or imitation grades of jewelry it is customary, where a number of jewels are set in close proximity, as in bars and clusters, to secure the jewels in their sockets by the method known as beading. A tool provided with a cupped end is driven into the surface of the setting close to the margin of the socket, so as to form a rounded boss or bead surrounded by a groove. As the bead is formed in the surface outside of the socket it serves merely an ornamental purpose, and the jewel is secured only by the bur formed of the metal displaced in forming the groove around the bead. This bur is irregular in amount and in the extent to which it overlaps the jewel, and it is easily bent or broken away, so that the jewels in settings of this character frequently become loose and fall out. The manufacture of settings of this kind, moreover, is difficult and requires great skill, owing to the exactness with which the beading must be performed in order to secure the jewels at all.

The object of the present invention is to produce a beaded setting in which the disadvantages above set forth are avoided and in which the jewels are securely fastened, while the labor and skill required in the construction of the setting are reduced to a minimum. To this end the setting is provided with projections adjacent to the sockets, which are adapted to be upset by a suitable cupped tool so as to form beads, and the beads so formed overlap the edges of the jewels and secure them firmly in place. In the formation of such beads the production of a bur is unnecessary and is avoided as far as possible, as the beads themselves are the retaining means, and thus the appearance as well as the mechanical structure of the setting is improved. This improved beading, in connection with sockets provided with curved walls partly surrounding the jewels and adapted to be bent or burnished against or over the edges

of the jewels, lends itself to the production of a variety of ornamental effects of which a few are indicated in the accompanying drawings.

I will now describe the embodiments of my invention illustrated in the accompanying drawings, and will thereafter point out my invention in claims.

In the drawings, Figure 1 is a front view of a jewel bar embodying my invention. Fig. 2 is a section on the dot-and-dash line in Fig. 1. Fig. 3 is a front view of a modified form of the invention, and Fig. 4 is a side view of the same. Fig. 5 is a front view of a second modified form of the invention, and Fig. 6 is a section on the dot-and-dash line in Fig. 5. Fig. 7 is a front view of a third modified form of the invention.

The body 1 of the setting is provided with jewel sockets 2 of any desired form, preferably closed sockets for the setting of jewels of low refractive power such as are commonly used in jewelry of this character, and upon the face of the setting are formed projections 3 located at or close to the sockets. When the jewel 4 has been inserted in the socket, as in Figs. 1 and 2, the projections 3 are upset by the operation of a tool similar to the ordinary beading tool, whereby they are shortened and widened to form beads. The widening of the bead-forming projections causes them to overlap the jewel, as at 5 in the drawings, and this effect is increased by directing the beading tool inwardly toward the jewel during the beading operation, so as to displace the metal inwardly. The setting is completed in the ordinary manner by forming beveled edges 6 to increase the ornamental effect of the setting.

In the form of the invention shown in Figs. 3 and 4 the sides of the settings are scalloped so as to form curved walls inclosing the sides of the sockets and adapted to be pressed or burnished against or over the edges of the jewels. The bead-forming projections are located in the angles between adjacent sockets and are formed as continuations of fluted lateral projections 7. In this form of setting great security is obtained by the combined action of the beads and the overlapping curved walls, and in appearance an effect is secured resembling the more expensive claw setting.

In the form shown in Figs. 5 and 6 the beads are used only at one side of the bar, the

jewels being secured at the other side by the curved wall which has a thin edge 8 adapted to be bent inwardly over the edges of the jewels.

5. Fig. 7 illustrates the invention as applied to cluster settings, or bars with a plurality of rows.

The jewel bars and clusters illustrated may be multiplied, added to and combined 10 in any desired manner to produce jewelry articles such as brooches, barettes, pins, combs, and other articles of a wide variety.

It is obvious that various modifications may be made in the embodiments of my invention illustrated in the drawings and herein described within the principle and scope 15 of my invention.

I claim:—

1. A jewel setting provided with a jewel 20 socket and with projections located adjacent to the socket, the projection being short and thick and of greatest thickness at the base so that they may be upset to form beads overlapping and securing a jewel in the socket.

25. 2. A jewel setting provided with a jewel socket and with upset beads substantially hemispherical in form and overlapping the socket so as to secure the jewel therein.

30. 3. A jewel setting provided with a plurality of adjacent jewel sockets and with projections located in the angles between the sockets, the projections being short and thick and of greatest thickness at the base so that they may be upset to form beads overlapping 35 and securing the jewels in the sockets.

35. 4. A jewel setting comprising a body portion provided with a jewel socket in its face, and upset beads integral with the body portion and projecting above the face thereof

and overlapping the socket so as to secure 40 the jewel therein, the beads being of a diameter greater than the amount of their projection from the body portion.

5. A jewel setting provided with a plurality of adjacent jewel sockets, curved walls 45 partly surrounding the sockets and having thin edges bent inward against or over the edges of the jewels in the sockets, and projections located in the angles between the sockets and upset to form beads overlapping 50 and securing the jewels in the sockets.

6. A jewel setting provided with a jewel socket, curved walls embracing the sides of the socket, and fluted lateral projections extending beyond the face of the setting to 55 form projections upset to form beads overlapping and securing the jewel in the socket.

7. The method of making jewelry which consists in forming a setting of malleable metal provided with a jewel-receiving socket 60 and with short, thick projections located adjacent to the socket, inserting a jewel in the socket, and upsetting and widening the projections so as to form beads overlapping the jewel and securing it in place. 65

8. A jewel setting comprising a metal body provided with a jewel-receiving socket and substantially hemispherical integral projections or beads of compressed and upset metal partially overlapping the socket and the 70 jewel therein.

In testimony whereof I affix my signature in presence of two witnesses.

HENRY W. FISHEL.
